UNITED STATES PATENT OFFICE.

LEWIS E. HENDRICKS, OF CAMPBELLSPORT, WISCONSIN.

LAMP.

1,185,904.

Specification of Letters Patent.

Patented June 6, 1916.

Application filed November 20, 1915. Serial No. 62,560.

To all whom it may concern:

Be it known that I, LEWIS E. HENDRICKS, a citizen of the United States, residing at Campbellsport, in the county of Fond du Lac and State of Wisconsin, have invented 5 certain new and useful Improvements in Lamps, of which the following is a specification, reference being had to the accompanying drawings.

10 This invention relates to certain improvements in lamps and has relation more particularly to a device of this general character especially designed and adapted for use in submersion; and it is an object of the 15 invention to provide a lamp of this general character which may be applied in operative position with convenience and facility and whereby the same may be readily adjusted to direct the beams of light in different directions.

20 Furthermore, it is an object of the invention to provide a lamp of this general character having novel and improved means whereby the possibility of the lenses or 25 closing glasses becoming clouded is substantially entirely eliminated.

The invention consists in the details of 30 construction and in the combination and arrangement of the several parts of my improved lamp whereby certain important advantages are attained and the device is rendered simpler, less expensive and otherwise 35 more convenient and advantageous for use, all as will be hereinafter more fully set forth.

The novel features of the invention will be carefully defined in the appended claims.

In order that my invention may be the better understood, I will now proceed to 40 describe the same with reference to the accompanying drawings, wherein—

Figure 1 is a view in side elevation of a lamp constructed in accordance with an embodiment of my invention, the coacting portion of a boat being shown in section; and Fig. 2 is an enlarged fragmentary view, partly in elevation and partly in section, illustrating certain details of the invention as herein included.

50 In the present embodiment, my improved lamp is shown as employed in connection with a boat for the purpose of under water illumination and, as herein disclosed, 1 denotes an elongated tubular member rotatably supported within the vertically spaced arms 2 carried by the bracket 3, said bracket

having its upper end returned, as at 4, to bridge an upper margin of the boat B and coacting with said boat is the clamping screw 5 threaded through the returned portion 4 and operating in a manner which is believed to be self-evident. The upper end of the member 1 is provided with a tubular extension 6 affording a means whereby axial rotation may be readily imparted to 65 the member 1.

The lower extremity of the member 1 is slightly offset and terminates in a socket 7 to which a bulb 8 is adapted to be connected, the socket 7 having in electrical connection 70 therewith in a conventional manner the conductors *a* disposed through the member 1 and the extension 6 and leading from a suitable source of electrical energy. The lower end of the member 1 has also secured thereto 75 the reflector head 10 substantially conical in form and having its outer end closed by the separated lenses or glasses 11 affording therebetween a dead air space 12 whereby it will be perceived that the possibility of said 80 glasses becoming clouded by steam generated from the heat emitted from the bulb 8 is substantially eliminated. As herein embodied, the lenses or glasses 11 are mounted within an annular member 14 bolted or 85 otherwise secured to the outer marginal portion of the reflector hood 10. I also find it of advantage to interpose between the hood 10 and the member 1 the supporting member or brace 15, for a purpose which is 90 believed to be self-evident.

From the foregoing description, it is thought to be obvious that a lamp constructed in accordance with my invention is of an extremely simple and comparatively inexpensive nature and is particularly well adapted for use by reason of the convenience and facility with which it may be assembled, and it will also be obvious that my invention is susceptible of some change and 100 modification without material departure from the principles and spirit thereof and for this reason I do not wish to be understood as limiting myself to the precise arrangement and formation of the several 105 parts herein shown in carrying out my invention in practice.

I claim:

1. An apparatus for submerged illumination comprising a bracket adapted to be 110 operatively engaged with a buoyant body and having vertically aligned arms, an elong-

gated vertically disposed member rotatably supported by the arms and extending above and below the body, a lamp operatively engaged with the lower end portion of the elongated member, the portion of the member above the body being angularly disposed to afford means whereby the elongated member may be rotated, the lamp carried by the lower end of the elongated member being angularly disposed relative to the elongated member.

2. An apparatus for submerged illumination comprising a bracket adapted to be operatively engaged with a buoyant body and having vertically alined arms, an elongated vertically disposed member rotatably

supported by the arms and extending above and below the body, a lamp operatively engaged with the lower end portion of the elongated member, the portion of the member above the body being angularly disposed to afford means whereby the elongated member may be rotated, the lamp carried by the member being arranged on an angle relative to the member less than 90°. 20 25

In testimony whereof I hereunto affix my signature in the presence of two witnesses.

LEWIS E. HENDRICKS.

Witnesses:

Jos. J. RODLER,
Jos. SCHRAMM.
